UNITED STATES PATENT OFFICE.

HENRY L. MARKLEY, OF MINNEAPOLIS, KANSAS.

WALL-PAPER PASTER AND TRIMMER.

1,371,920.

Specification of Letters Patent. Patented Mar. 15, 1921.

Application filed July 21, 1919. Serial No. 312,358.

To all whom it may concern:

Be it known that I, HENRY L. MARKLEY, a citizen of the United States, residing at Minneapolis, in the county of Ottawa and State of Kansas, have invented new and useful Improvements in Wall-Paper Pasters and Trimmers, of which the following is a specification.

The object of the invention is to provide a machine which will apply paste to wall paper and trim the selvage edge thereof preparatory to the paper's being applied to the wall. To this end the invention comprises a main frame, a supply roll spindle on which the roll of wall paper to be trimmed and pasted is carried, intermediate rollers over which the wall paper passes from the supply roll to be brought into contact with a paste applying roll rotating or traveling in a suitable paste receptacle.

Attendant on the paste applying roll there is a scraper element which may be adjusted toward and away from the paper after the latter has passed over the paste roll. By means of this scraper the thickness of the paste applied to the paper is regulated.

A further object of the invention is to provide a machine of the character described which is simple in construction, durable and effective in operation and inexpensive to manufacture.

Other and further objects appear in the following description wherein the invention is set forth in detail. To the exact construction in which it is shown and described, the invention is not to be restricted. The right is reserved to make such changes or alterations as the actual reduction to practice may suggest, in so far as such changes or alterations are compatible in spirit with the annexed claims.

In the accompanying drawings:

Figure 1 is a top plan view of the improved machine.

Fig. 2 is a view similar to Fig. 1 but omitting the hingedly mounted top member and its attendant rolls.

Fig. 3 is an end elevational view of the machine.

Fig. 4 is a further end elevational view but looking at the opposite end from that shown in Fig. 3.

Fig. 5 is a section on the line 5—5 of Fig. 1

Fig. 6 is a section on the line 6—6 of Fig. 2

Fig. 7 is a section on the line 7—7 of Fig. 1

Fig. 8 is a section on the line 8—8 of Fig. 2.

As shown, the invention comprises a box like frame 1 having the shape preferably of a rectangular parallelepiped but having one side wall cut away, as indicated at 2, the top of the frame being left open so that paper carrying rolls supported by a supplementary frame may engage paper carried in the main frame. At that side opposite the open side 2, an arcuate plate 3 is carried, this plate 3 attaching to the frame at the upper edge adjacent the closed side and attaching to the closed ends of the frame at a point between the center of the latter and the open side. This plate 3 constitutes the bottom of a paste reservoir in which a supply of paste, such as is indicated at 4 may be carried.

A paste supply drum or roll 5 is employed and is rotatably mounted in the paste reservoir by means of trunnions 6 carried on its ends, one of these trunnions resting in a suitable bearing in one end of the frame 1 and the other being engaged in a bearing 7 which is carried in a sleeve 8 mounted on the opposite end of the frame. A spring 9 is inclosed within the sleeve and bears on the bearing element 7 tending to force it toward the drum 5 but the bearing element is provided with a stem 10 projecting from the sleeve member 8 and formed with a knurled head 11 at its end by means of which it may be moved against the pressure of the spring 9 to release the bearing 7 from its attendant trunnions 6. Thus, when it is desired to remove the drum 5 for the purpose of cleaning the paste reservoir, the bearing 8 and the means by which it is mounted provide for the ready removal of the drum.

The paste applying drum 5 is rotated by the paper which passes over it, the frictional contact of the paper effecting the rotation of the drum which moving in the paste 4 carried in the reservoir carries the latter up 105 for application to the passing paper.

At the open side of the frame 1, the roll of paper to be trimmed and pasted is carried. To provide means for mounting the usual roll in place, the two ends of the frame 1 are 5 equipped with sleeves or thimbles 12 and 13 respectively, the thimble 12 receiving a stud 14 which stands within the frame and has its stem 15 projecting out of the frame through the thimble 12. A spring 16 sur- 10 rounds the stem (which is of less diameter than the stud proper) and is pressed between the end of the thimble and the shoulder formed at the junction of the stud with its stem. This spring, therefore, tends to force 15 the stud in the direction of the opposite side of the frame. The stud 14 at its inner end—that is, the end projecting into the inside of the frame—carries a disk 17 which is formed with a hub 18 through which there 20 passes a set screw 19, the latter bearing upon the stud and securing the disk thereto. From its inner end the stud is bored in the direction of its length to receive one end of a spindle 20, the latter being designed for 25 carrying means for a roll to be pasted. On the opposite end of the spindle 20 there is fixedly attached a disk 21 which, together with the disk 17, serves as a flange for the spindle to preclude longitudinal movement 30 of the paper roll along the spindle once it is attached thereto. That end of the spindle 20 at which the disk 21 is carried has a pivotal bearing in the bearing member 22 which is similar to the bearing element or 35 member 7. This bearing member 22 is carried in the thimble 13. Its inner end stands within the frame and its stem is inclosed in the thimble, as spring 23 tending normally to draw the bearing member 22 away from 40 the connecting end of the spindle 20. Acting in opposition to the spring, however, there is a screw 24 which is formed with a knurled head 25. This screw threads into the thimble from the outer end thereof and 45 bears against the end of the stem of the bearing member 22. The screw may be employed therefore to shift the spindle 20 in an axial direction and this construction provides for properly positioning the roll of 50 paper relative to the other parts of the machine, so that the selvage edges may be brought into position for severance at the proper places.

Guard plates 26 are attached to the bottom 55 of the frame adjacent either end thereof and extend upwardly and partly overhang a roll of paper when the latter is placed upon the spindle 20.

Rotatably mounted in the frame and be- 60 tween the spindle 20 and the adjacent side of the paste reservoir there is a pair of trim- 65 ming rolls 27 which are carried on a common shaft 28, this latter being rotatably mount- ed in trunnion bearings 29 mounted in op- posite ends of the frame, the bearings 29

being secured to the frame by means of threaded stem portions 30 which project through slots 31, these threaded stem portions 30 receiving the nuts 32 which bear against the outer faces of the ends of the 70 frame and secure the bearings in place. The slots 31 are diagonally disposed and this construction makes for the adjustment of the bearings to move the rolls 27 toward or away from the roll of paper carried on the 75 spindle 20.

The rolls 27 are loosely mounted upon their attendant shaft 28 and their opposite ends are held in close proximity to relatively narrow rolls 33 carried by the shaft ad- 80 jacent its opposite ends but fixedly attached thereto. Spacing washers 34 are interposed between the ends of the rolls 27 and the adjoining faces of the rolls 33 for the pur- 85 pose of providing a peripheral slot in which a circular selvage trimming knife may oper- 90 ate. A spring 35 surrounds the shaft 28 and is pressed between the adjoining ends of the rolls 27 and tends to keep them in contact with the spacing washers 34. This con- 95 struction provides for shifting either of the rolls 27 away from its attendant small roll 33 for the purpose of cleaning out the slot provided by the spacing washers between the two should such slot become clogged up as is a possible condition in practice.

The circular selvage trimming knives op- 100 erate in the slots provided by the em- ployment of the spacing washers 34 and each of these knives comprises a beveled disk 36 securely attached to a roll 37 formed with a hub 38, the latter rotating on a stud 39 projecting laterally from an arm 40 ad- 105 jacent the one end of the arm. The arm 40 adjacent the other end has a similar later- ally projecting stud of shorter length which enters and is carried in an appropriate eye formed at the upper end of a standard 41 which is attached to the frame. A set screw 42 passes readily through the eye and bears 110 upon the stud 41 to hold the latter securely attached to the standard. Between the disk 36 and the arm 40, the stud 39 carries a spring 43 which surrounds the stud and has one end bearing against the disk. This 115 spring would force the disk, the hub and the wheel off the stud were not a cotter pin 44 provided and inserted diametrically through the stud adjacent its free end. This pin, therefore, takes the place of the hub 120 38 while the spring precludes too free a rotary movement of the knife during its trimming operation. The retardation of ro- 125 tation afforded by this spring makes for more effective trimming of the selvage than would be possible were the knife too freely rotated on its attendant stud. The selvage edge trimmed off is, by this construction, more effectively kept from clogging.

The frame 1 adjacent each end is pro- 130

vided with a standard 41 and each standard supports a cutting disk 36 and its attendant parts as has just been described, each cutting disk operating in the place or 5 slot provided by the spaced washers 34 between the rolls 33 and 27.

A supplementary frame 44' is hingedly attached to the main frame 1 above the spindle 20 as indicated at 45. This supplemental frame 44' is an open frame comprising two end rolls 46 and two longitudinally disposed plates 47 and 48 which connect the end rolls together.

Mounted in the supplemental frame 44' 15 there is a pressure roll 49 which is carried on an appropriate spindle 50, the latter being rotatably mounted in bearings 51 carried by the opposite end rails 46. These bearings 51 are oval shaped in cross section 20 with the longest dimension of the oval disposed substantially vertically, so that the roll 49 may yield toward and away from the rolls 27 into contact with which the roll 49 forces the paper passing from the 25 roll carried on the spindle 20.

Disposed in advance of the roll 49—that is, between that roll and the paste applying roll 5 there is a roll 52 and two coöperating rolls 53. The latter two rolls are mounted 30 on a common shaft 54 while the former roll is mounted on a shaft 55.

The two shafts 55 and 54 are rotatably mounted in the opposite end of the levers 56 which are pivotally mounted, as indicated at 35 57', on the opposite end rolls 46 of the supplemental frame. The pivot points of the levers are adjacent those ends wherein the shaft 55 is mounted. Shaft 54 being mounted in the ends of the longer arm of the levers 40 over the pivot points 21 being disposed to one side of the levers, the tendency of gravity will be to cause those ends of the lever in which the shaft 54 is mounted to drop and pins are provided and attached in the opposite side bearings of the upper frame to 45 limit the distance to which the ends of these levers may drop. The levers 56 are Z-shaped as shown and the legs in which the shaft 54 is mounted are depending legs; the 50 axis of the rolls 53 is therefore normally lower than the axis of the roller 52, and since the levers 56 are pivotally mounted, any tendency to rest rolls 53 will result in lowering the roll 52.

The roll 52 is designed as a pressing roll 55 for keeping the paper in contact with the paste applying roll 5 and as the paper is led from the supply roll carried on the spindle to the paste roll 5 it passes between the rolls 49 and 27, then underneath the rolls 53 and then over the roll or drum 5. Obviously when the paper is tensioned between the point where it leaves the rolls 27, and the point where it contacts with the rolls 5 it 60 will tend to raise the rolls 53 with a result-

ant depression of the roll 52, the latter then contacting with the paper as it passes over the roll or drum 5 and maintaining it in firm contact with the drum 5 throughout the length of the latter.

70

On the opposite side of the drum 5 from the rolls 53 and 52, an idle roll 57' is carried, this roll being mounted on a shaft or spindle 58 which is journaled in appropriate bearings carried by the side rails 46 of the supplemental frame.

75

The paper in leaving the paste applying roll passes under this idle roll 57' and in order that the layer of paste to be applied to the paper may be regulated, there is provided a double edged scraper 59 which is carried by a shaft 60 rotatably mounted in opposite ends of the main frame 1. This scraper 59 on one of its elements is formed with the coarse scraping edge 61 and on the other of its elements with a fine scraping edge 62. Either of these scraping edges is adapted to be brought into close proximity to the pasted face of the paper as it leaves the drum 5 and passes beneath the idle roll 90 57. In order that it may be positioned with reference to the passing paper as desired, the shaft 61 by which it is carried is equipped exterior to the main frame with a toothed disk 63 lying adjacent one end of 95 the main frame, a pivotally mounted pawl 64 being mounted adjacent the disk for engagement with the teeth thereof so as to maintain the scraper edge elevated to the proper position for the desired contact with 100 the passing paper.

In the operation of the machine, the usual roll of paper is attached to the spindle 20 after the latter has been removed by forcing the bearing stud 12 back against the pressure 105 of its spring 16. Since that end of the spindle which engages the stud carries no disk, the spindle may be readily inserted through the roll of paper and then attached into position, the bearing stud moved back as before 110 to permit its attachment. If it is necessary to adjust the roll longitudinally to properly position it so that its selvage edges may be trimmed at the line, the screw 24 is turned either right handedly or left handedly to 115 move the roll in the direction desired. If the screw be turned in one direction the spindle 20 is forced longitudinally in the direction of that side of the main frame carrying the thimble 12, this movement of 120 the spindle being against the pressure of the spring 16. If the screw be turned in the opposite direction, the spring 23 in the thimble 13 operates to draw the bearing element within the thimble and the spring 16 125 serves to force the spindle 20 in the direction of the bearing member or element 22. Thus the spindle 20 may be adjusted in either direction to properly position the roll for the cutting of its selvage edges.

130

The roll having been placed on the spindle as aforesaid the set screws 42 are loosened when the arms 40 may be swung upwardly to lift the trimming or cutting knives out of their position within the space between the rolls 27 and 33, the supplemental frame being of course raised on its hinged connections to permit access to these set screws. The paper is then drawn off the supply roll and over the rolls 27, the knives being restored to their normal positions, when they will sever the paper at the selvage edges. The paper is then drawn over the drum 5 after which the supplemental top is swung down to its normal position which is held by the spring clips 65 attached to the ends of the main frame and engaging the side rails 46 of the supplemental frame. Upon the swinging of the supplemental frame to this position, the roll 49 bears against the paper forcing it into contact with the rolls 27, the rolls 53 at the same time contacting with the paper and being raised as a result of such contact, whereupon the roll 52 is swung down in the direction of the drum and presses upon the paper forcing it into contact with the drum 5, that end of the paper projecting from the machine passing under the idle roll 52. As the paper is drawn off the supply roll by pulling on this projecting end, drum 5 is rotated and because of its immersion in the paste 4, the latter is raised and brought into contact with the paper and the layer of paste thus applied is regulated as desired by the proper adjustment of the scraper 60 by means of its toothed disk and pawl. The position of the scraping edge of the scraper whether it be the edge 61 or 62 determines the quantity of paste left on the paper and at the same time crushes or knocks off any clogs of paste that might be applied during the operation of the machine.

The invention having been described, what is claimed as new and useful is:

1. In a machine of the kind described, a main frame, a paste reservoir carried by the main frame, a rotatably mounted drum carried by the main frame and turning in the paste reservoir, a double edged scraper carried by the main frame and adapted to have either of its edges engaged by the paper leaving the drum for the purpose of crushing clogs of paste or removing the same from the paper when they are applied in the operation of the drum.

2. In a machine of the kind described, a main frame, a paste reservoir carried by the main frame, a rotatable drum carried by the main frame and operating in the paste reservoir, rotatably mounted trimming rolls carried by the main frame, circular knives carried by the main frame and coöperating with the trimming rolls, a supply roll supporting means carried by the main frame, a

supplemental frame hingedly attached to the main frame, and supplemental rolls carried by the supplemental frame and holding paper passing from the supply means into contact with the trimming rolls and with the drum.

3. In a machine of the kind described, a main frame, a paste reservoir carried by the main frame, a rotatable drum carried by the main frame and operating in the paste reservoir, a pair of trimming rolls rotatably mounted in the main frame, circular knives coöperating with the trimming rolls, supporting means for said knives whereby they may be swung toward and away from the trimming rolls, a supplemental frame hingedly attached to the main frame, and supplemental rolls carried by the supplemental frame and operating to hold paper passing from the supply means into contact with the trimming rolls and with the drum for the purpose and in the manner herein specified.

4. In a machine of the kind described, a main frame, a paste reservoir carried by the main frame, a rotatable drum carried by the main frame and operating in the paste reservoir, a scraper provided on its opposite longitudinal edges respectively with fine and coarse scraping edges, and means for rotating the scraper to bring either of said edges into contact with the pasted surfaces of the web after it leaves the said drum.

5. In a machine of the kind described, a main frame, a paste reservoir carried by the main frame, a rotatable drum carried by the main frame and operating in the paste reservoir, a scraper provided on its opposite longitudinal edges respectively with fine and coarse scraping edges, and shaft rotating means on the frame and carrying said scraper, a toothed disk mounted on the shaft exterior to the frame, and a pawl carried by the frame and engaging the teeth of the disk to maintain various positions of either of said scraping edges relative to the pasted face of the web as it leaves the said drum.

6. In a machine for the purpose indicated, a main frame, a supply roll supporting means carried by the main frame, rotatably mounted trimming rolls carried by the main frame and in advance of the supply roll supporting means, circular knives, and adjustably mounted swinging brackets provided with studs on which the knives are rotatably mounted, the said knives coöperating with the trimming rolls to remove the selvage edges from a web of paper being drawn from a supply roll carried on said supply roll supporting means.

7. In a machine for the purpose indicated, a main frame, a supply roll supporting means carried by the main frame, a transverse shaft rotatably mounted in the main frame in advance of the supply roll support-

- ing means, a pair of relatively narrow-faced rolls mounted on said shaft adjacent its ends, trimming rolls carried on said shaft and longitudinally movable thereon, a spring 5 carried on the shaft and bearing against the adjacent ends of the trimming rolls, spacing means carried on the shaft interposed between the remote ends of the trimming rolls and the said narrow rolls, and rotatably 10 mounted circular knives carried by the main frame and having their cutting edges disposed between said narrow rolls and said trimming rolls in the manner and for the purpose specified.
- 15 8. In a machine for the purpose indicated, a main frame, a paste reservoir carried by the main frame, a rotating drum carried by the main frame with its lower peripheral face immersed in the contents of the paste 20 reservoir, a supply roll supporting means carried by the main frame, a supplemental frame hingedly attached to the main frame, levers carried by the supplemental frame on opposite sides thereof and pivotally mounted intermediate their ends, shafts spanning
- the supplemental frame and rotatably mounted in the ends of the said levers, a relatively long roll mounted on one of said shafts, a pair of spaced rolls mounted on the other of said shafts, the said levers being 30 disposed between the supply roll supporting means and the said drum, and an idle roll carried by the supplemental frame and disposed in advance of said drum.
9. In a machine for the purpose indicated, 35 a main frame, paste applying means carried by the main frame, and a supply roll supporting means carried by the main frame and consisting of a longitudinally yieldable stud mounted on one side of the main 40 frame and formed at one extremity with a bearing socket, a disk secured to said stud, a shaft having one end entering the socket in said stud, a disk carried by the shaft adjacent the other end thereof, and a bearing 45 member receiving the said other end of the shaft in the manner and for the purpose specified.

In testimony whereof I affix my signature.
HENRY L. MARKLEY.
